DISPENSING TOP FOR WHIP CREAM CONTAINERS OR THE LIKE

Leonard M. Collins, Los Angeles, Calif., assignor to Pressure Dispensers, Inc., Hollywood, Calif., a corporation

Application June 13, 1955, Serial No. 36,473

Term of patent 14 years

(Cl. D62—2)

Fig. 1

Fig. 2

Figure 1 is a perspective view of a dispensing top for whip cream containers or the like, embodying my new design;

I claim:

The ornamental design for a dispensing top for whip cream containers or the like, substantially as shown.
